UNITED STATES PATENT OFFICE

126,708

DESIGN FOR A COMMERCIAL BUILDING

Wesley R. Pierson, Minneapolis, Minn.

Application December 16, 1940, Serial No. 97,350

Term of patent 14 years

To all whom it may concern:

Be it known that I, Wesley R. Pierson, a citizen of the United States, residing at Minneapolis, in the county of Hennepin and State of Minnesota, have invented a new, original, and ornamental Design for a Commercial Building, of which the following is a specification, reference being had to the accompanying drawings, forming part thereof.

Fig. 1 of the drawings is a plan view of the building showing my new design.

Fig. 2 is a front elevational view of the building.

Fig. 3 is a side elevational view of the building viewed from the left.

Fig. 4 is a rear elevational view of the building.

I claim:

The ornamental design for a commercial building, as shown.

WESLEY R. PIERSON.
